STAMP

Herbert Schönfelder, Leipzig, Germany, assignor
to Elisabeth Tietze, née Friedrich, Molkau/Leip-
zig, Germany

Application December 14, 1932, Serial No. 647,204
In Germany May 3, 1932

5 Claims. (Cl. 101—111)

This application was filed in Germany on the
3rd May, 1932.

The present invention relates to adjustable
rubber stamps, of the kind used as date stamps
or for other purposes, in which a set of endless
rubber bands carrying printing characters and
extending over a fixed support and a set of in-
dependent pulleys are used, the pulleys being
adapted to be turned independently to bring any
10 character into printing position.

One very unpleasant drawback of these known
stamps is the fact that in using the stamps
the hands, the paper and other objects are liable
to be soiled owing to the fact that the rubber
bands carrying the printing characters are lat-
15 erally not covered. Another drawback of this
lack of lateral cover is the fact that the stamp
bands and the printing characters become very
rapidly soiled, whereby the setting of the print-
ing characters is rendered difficult. The dura-
20 bility of the stamp is also very considerably
reduced. The known constructions of these
stamps are somewhat difficult to put away and
it is therefore usual to put a stamp after use
25 upon an open ink pad, which again leads to
soiling of the stamp bands by the ink of the pad.

In order to obviate these drawbacks it has
already been proposed to make the stamp frame
or casing in the form of a container consisting
30 of several parts, which has only the necessary
openings for setting the bands and for making
the impression. The construction of these im-
proved band stamps is, however, very compli-
cated, which makes the manufacture very ex-
35 pensive and also renders the assembling and dis-
mantling of the parts very difficult.

The present invention consists in an improved
construction in which the container-like frame
of the stamp consists of only two identical parts
40 which are connected together by a very simple
means so that an extremely simple construction
is attained. This object is, according to the
invention, attained by using a container-like
frame which has only such openings as are re-
45 quired for setting the bands and for making
the impression, and is divided along a symmetry
plane passing through the axis of the pulleys
and the printing bar in the longitudinal direc-
tion, so that the container consists of two entirely
50 identical halves which are connected together
by any suitable means. Preferably the two con-
tainer halves are inserted in known manner
with the lower ends of their end walls into the
cup-shaped printing bar so that the latter is
55 utilized as a means for connecting the two

halves. The halves are, moreover, connected
above the pulleys by means of eyes which en-
gage each other and a pin passed through the
eyes. In order to dispense with further sepa-
rate parts, the stamp handle or knob is likewise
5 divided along the plane of division of the con-
tainer, each half of the handle or knob being
made in one piece with the corresponding con-
tainer half. This construction facilitates the
manufacture of the stamp container from a 10
pressed and artificial material, such as bakelite,
papier mâché, celluloid and the like, whereby
reduction of the weight of the stamp and a very
pleasant appearance are obtained. The manu-
facture of the stamp is, moreover, simplified by 15
the fact that the band pulleys together with
the hand discs serving for their setting are
drawn from sheet iron, and pulleys being, dur-
ing the drawing operation, slightly ribbed and
consequently roughened upon their peripheral 20
surfaces bearing the rubber bands, for the pur-
pose of increasing frictional resistance between
the rubber bands and the pulleys. When using
wide band pulleys, a cover disc is pressed into
25 the cavity of the pulley, whereby two bearing
surfaces are obtained between the pulley and the
spindle.

According to the invention the stamp pad con-
tainer is provided with a vertically guided frame
which serves for receiving the lower end of the 30
stamp, and is for the purpose of inking the
stamp, depressed together with the stamp against
the action of pressure springs. When the stamp
is inserted into the frame, it is normally held
35 by the springs away from the inking pad. 35

The accompanying drawing shows by way of
example one construction embodying the fea-
tures of the invention.

Fig. 1 is an elevation of the stamp, the front
half of the container being removed, and one of 40
the pulleys being shown in section.

Fig. 2 is an inner view of one of the container
halves.

Fig. 3 is a section on the broken line A—B of
Fig. 1.

Fig. 4 is a section on line C—D of Fig. 2.

Fig. 5 is a partial elevation of the inking pad
container, and

Fig. 6 is a section and partly an end view of the
inking pad container.

The stamp comprises as usual several band
pulleys 2 mounted upon a spindle 1, over which
run endless rubber bands 3 bearing the printing
characters the bands being also guided over a
printing or support bar 4. The printing bar con- 50
55

sists of a piece of sheet iron having upturned longitudinal edge portions and similarly upturned end edge portions. The printing bar 4 and the pulley spindle 1 are held by the stamp container 5 at such a distance apart as to put the rubber bands under a slight tension. Whereas in the known rubber bands, the frame is in the form of a U, the pulley spindle being mounted in the lateral limbs and the handle being fixed to the middle portion of the U, the container is, according to the invention, divided along a plane of symmetry passed through the axis of the pulley spindle and the longitudinal middle line of the printing bar. The two halves of the container 15 are completely identical, each half having two end walls 5 in which are provided the bearings 6 for the pivot pins 7 of the pulley spindle 1, and an upper wall 9. The wall 9 is formed with a knob half portion 8 and with projecting hinge eyes 10 which alternate with intervening recesses 11 of corresponding width. Each container half moreover has a lateral enclosing wall 12 which conforms to the periphery of the band pulleys and the path of the bands. In this lateral enclosing wall are provided slots 13 through which project peripheral segments of operating or setting discs 14 appertaining to the band pulleys. In the bottom edge of each end wall 5 is formed a notch 15. The four notches 15 serve for receiving the upturned edges of the printing bar 4.

The band pulleys 2 are each drawn in one piece with the appertaining operating disc 14, the edge portion of the pulley end wall bordering the opening through which the spindle passes, being bent inwards in order to provide a sufficiently large running and bearing surface of the pulley upon the spindle. The cylindrical peripheral surface of the band pulley upon which the band runs is, during the drawing operation, slightly ribbed 40 by the use of a suitably shaped matrix, as indicated at 16 in Fig. 1. Those pulleys which have a considerable width are provided with a pressed-in end cover 17, which serves for reinforcing the pulley and is provided adjacent to the spindle with a running and bearing surface. The wide pulleys have therefore two bearing and running surfaces.

The assembling of the stamp parts is effected in the following manner. The pulleys together with the rubber bands are first slid upon the pulley spindle. The printing bar is passed through the bands and is inserted with its lateral flanges into the notches 15 of the container halves, the spindle is then inserted with its pivots 7 into the bearings 6 of one container half, the bands being at the same time slightly tensioned. The other container half is then pressed into the first container half. The eyes 11 of the two container halves engage between each other and into the corresponding recesses of the other half, whereby the bores 18 of the hinge eyes 10 of both container halves are brought into line. A pin 25 is then inserted through the registering hinge eyes. It will be seen that the whole inner mechanism is entirely enclosed by the container, with the exception of the small opening required for printing and the small openings required for peripheral segments of the operating discs 14. 70 These openings are formed by slots 13 of the container halves. The two knob halves 8 form together a closed knob, the cavity of which may be utilized for the reception of spare parts, stamp bands, pulleys and the like.

75 The container halves may be made of any

material capable of being pressed or cast, for instance sheet iron, artificial substances such as bakelite or the like, and other ordinary casting or spray casting may be employed. The pulleys of the stamp bands may also be made of similar artificial materials. The container may comprise several parts, for instance the knob may form a separate part.

The inking pad container 19 shown in Figs. 5 and 6 has a frame portion 23 which is vertically guided against the pressure of springs 22 by means of pins 20 and grooves 21, and is so adapted to the lower end of the stamp that upon insertion of the stamp into the frame, the printing characters located upon the printing bar are held away from the inking pad 24. The inking of the characters can be effected only by depressing the stamp together with the frame 15 against the action of the springs. In this way the inking pad container is utilized both 20 for the reception of the stamp when the latter is not used, and serves also for protecting the stamp against soiling.

I claim:

1. In a stamp the combination of: a casing 25 including a knob; a spindle mounted in said casing; a printing bar carried by the casing; a plurality of pulleys independently rotatable upon said spindle and provided with discs slightly projecting from said casing, said disc serving for setting said pulleys from the outside; bands carrying printing characters, said bands being passed each over a pulley and the printing bar; said casing including the knob consisting of two identical halves, the plane of division of the 35 casing passing through the axis of the spindle upon which the pulleys are mounted, and also passing through the printing bar, substantially as described.

2. In a stamp the combination of: a casing; 40 a spindle mounted in said casing; a printing bar carried by the casing; a plurality of pulleys independently rotatable upon said spindle and provided with discs slightly projecting from said casing, said discs serving for setting said pulleys 45 from the outside; bands carrying printing characters, said bands being passed each over a pulley and the printing bar; said casing forming a container substantially enclosing completely the pulleys and the bands, with the exception of an 50 opening corresponding to the printing bar and with the exception of slots for the passage of portions of the peripheries of the setting discs, said casing being composed of two substantially identical halves, the plane of division passing 55 through the axis of the spindle upon which the pulleys are mounted and the longitudinal middle line of the printing bar; each half of the casing having at its lower end notches for the reception of the printing bar and also having 60 above the pulleys hinge eyes alternating with recesses of corresponding width, said two halves of the casing being secured together at one end by the printing bar inserted into the notches, and at the other end by a pin passed through the 65 hinge eyes, substantially as described.

3. In a stamp the combination of: a casing; a spindle mounted in said casing; a printing bar carried by the casing; a plurality of pulleys independently rotatable upon said spindle and provided with discs slightly projecting from said casing, said discs serving for setting said pulleys from the outside; bands carrying printing characters, said bands being passed each over a pulley and the printing bar; said casing forming 75

5 a container substantially enclosing the pulleys and the bands with the exception of an opening corresponding to the printing bar and slots for portions of the edges of the setting discs; said casing consisting of two substantially identical halves, the plane of division passing through the axis of the spindle upon which the pulleys are mounted and the longitudinal middle line of the printing bar; each casing half being made in one 10 piece with a hollow member constituting one half of knob, the cavity within the knob serving for the reception of spare parts, substantially as described.

10 4. In a stamp the combination of: a casing; a spindle entirely enclosed within said casing; a printing bar carried by the casing; a plurality of pulleys independently rotatable upon said spindle and provided with discs slightly projecting from said casing, said discs serving for setting said pulleys from the outside; bands carrying printing characters, said bands being passed each over a pulley and the printing bar; said casing consisting of two exactly identical halves, the plane of division of the casing passing 20 through the axis of the spindle upon which the

25

pulleys are mounted, and also passing through the printing bar; each casing half having internal half cylindrical recesses outwardly closed, the recesses of both casing halves forming bearings of said entirely enclosed spindle, substantially as described. 5

5. In a stamp the combination of: a casing including a knob; a spindle mounted in said casing; a printing bar carried by the casing; a plurality of pulleys independently rotatable upon 10 said spindle and provided with discs slightly projecting from said casing, said discs serving for setting said pulleys from the outside; bands carrying printing characters, said bands being passed each over a pulley and the printing bar; said 15 casing consisting of two exactly identical halves, the plane of division of the casing passing through the axis of the spindle upon which the pulleys are mounted, and also passing through the printing bar and a knob, said knob consisting of two 20 identical halves each formed integrally with one of the identical halves of said casing substantially as described.
